DESIGN FOR A STOCKING

Samuel A. Roth, Cleveland, Ohio

Application March 29, 1941, Serial No. 99,995

Term of patent 14 years

To all whom it may concern:

Be it known that I, Samuel A. Roth, a citizen of the United States, residing at Cleveland, county of Cuyahoga, and State of Ohio, have invented a new, original, and ornamental Design for Stockings, of which the following is a specification, reference being had to the accompanying drawing, forming a part thereof.

ing, with parts shown in perspective, embodying my new design, and

Figure 2 is a fragmentary perspective view of the stocking, looking at the same from the rear.

The top of the stocking is conventionally plain.

I claim:

The ornamental design for a stocking, as shown and described.

SAMUEL A. ROTH.
